Application December 5, 1929, Serial No. 411,714

28 Claims. (Cl. 246—8)

This invention relates to telephone systems in general, but is more particularly concerned with telephone systems for use in connection with railroads. The object of the invention broadly stated 5 is the provision of new and improved apparatus and circuits for supplying telephone service on and between railroad trains and between trains and wayside points.

The utility of direct communication between 10 railroad trains using the same track systems and between trains and a wayside point, such as a dispatcher's office, has long been recognized, and numerous systems, both telephonic and telegraphic have been devised for this purpose. In 15 so far as applicant is aware, none of these systems has been entirely successful from a commercial standpoint due either to inherent operating defects or to excessive cost. Such systems may be divided roughly into two classes, namely; inductive telephone systems and radio telephone systems. The instant invention may be identified as belonging to the inductive type and, therefore, only such systems will be discussed.

Basically the inductive train telephone system 20 consists of a telephone line inductively connected with telephone apparatus carried by a train. The method by which this connection is made varies considerably in different systems. It has been found most satisfactory, however, to employ an intermediate circuit to which both the 25 train apparatus and the telephone line may be inductively connected as required. It is obvious that if the rails of the track can be used as a part of the intermediate circuit there will be considerable saving in conductors required for this 30 purpose. There are numerous obstacles in the way of such use, for example the grounded condition of the rails and their electrical discontinuity for signalling purposes. Another obstacle 35 is the great amount of inductive disturbance picked up by such circuits from nearby power lines, electric railways, etc. These obstacles have been successfully overcome in the instant invention, as will be pointed out hereinafter.

In order that the utility of the invention may 40 be better appreciated the conditions under which it is to be used will be discussed briefly. In present day railroad practice the track is usually divided into electrically insulated sections 45 or blocks for signalling purposes. Each block is provided with relay equipment which is controlled by trains passing through the block for the purposes of operating various signal mechanisms. In addition, some railroads are provided with systems for automatic train control, 50

the Intermittent Electrical Contact method, such as described in Bulletin No. 5 of the American Railway Association Committee on Automatic Train Control, published June, 1929, being more or less standard for this purpose. Telephone apparatus must be capable of functioning in conjunction with these signalling and control systems, without interfering in any way with their 5 operation.

It is an object of the invention to produce a 10 telephone system which will operate satisfactorily under the above conditions without interfering in any way with existing signal and control apparatus, and without necessitating any 15 major changes in such apparatus. Another object is the utilization of existing apparatus to the fullest degree in order that both first cost and upkeep may be reduced to a minimum. Other objects and features not specifically mentioned 20 at this time will be discussed along with the operation of the system, which will be described in detail in later paragraphs, reference being had to the accompanying drawings, comprising Figs. 1 to 8, inclusive of which Fig. 1 shows a side view of a railroad car with the inductor in place; 25 Figs. 2 and 3, are, respectively, an end view and a top view of the apparatus shown in Fig. 1; Fig. 4 shows a section of track arranged to use the rails as a part of the telephone circuit; Fig. 5 shows a transmitting and receiving set; Fig. 6 shows a 30 stretch of track arranged for signalling from the train to the dispatcher; Fig. 7 shows another section of track arranged with a wire between the rails for talking purposes; and Fig. 8 shows a further modification of the track circuit disclosed in Fig. 4. 35

Fig. 1 shows diagrammatically a side view of a railroad car equipped with telephone apparatus. The inductor I which consists of a number of turns of wire is mounted on a frame beneath the body I of the car at a point between the rails over which the car runs. This coil or inductor is mounted sufficiently high to clear ordinary obstructions which may be present along the track, of which one rail 2, and ties such as 7 are shown. 40 The inductor is connected to the telephone set TT by means of the transformer 8. While no particular type of car is shown, it is to be understood that this apparatus may be mounted on a locomotive tender or the locomotive itself, 45 on the caboose, or on passenger coaches with equal facility. Fig. 2, is an end view of equipment shown in Fig. 1 and illustrates the manner in which the inductor is mounted between the 50 wheels. The inductor frame is normally carried 55

in a vertical position as shown in Fig. 2, but may be turned to a horizontal position when required for purposes which will be discussed hereinafter. In this figure is also shown a conductor 9 carried 5 on the ties between the rails. The purpose of this conductor will be fully explained in later paragraphs.

Fig. 3 is a top view of equipment shown in 10 Figs. 1 and 2, and illustrates the location of the inductor from another angle.

Fig. 4 shows a stretch of track divided into 15 sections or blocks A to F, inclusive. The signalling apparatus for each block includes a relay bridged across the two rails at one end of the block, and a source of current or battery bridged across the rails at the other end of the block. The signal relay is normally energized, and retracts its armatures only when it is short-circuited by the entry of a train into the block. 20 Alternate blocks, such as C and E are provided with a relay connected in series with the battery across the two rails. This relay is of relatively low resistance and is stiffly adjusted so that it does not operate in series with the above mentioned signal relay. However, when a train passes 25 through the block a relatively low resistance circuit exists between the rails through the wheels and trucks of the train, and the relay operates from the increased current flow.

30 The previously referred to intermediate circuit for connecting the train telephone set with the dispatcher's line is a closed loop circuit of which the two rails of the block in parallel are connected by a conductor which is carried on a 35 pole line adjacent to the track. It will be noted that transformers are included in this circuit at each end of the block providing an inductive connection with the circuit of the adjacent block. However, alternate transformers, such as 4TB 40 and 4TD, are normally rendered ineffective by a short-circuit in one winding and the opening of the other winding. It, therefore, follows that the 45 circuits of the two blocks are always inductively connected, and as will be explained later, under certain conditions four, six, or more blocks may be so connected. The transformers are connected up so that a transposition exists between adjacent block circuits whether permanently or 50 temporarily connected. Each pair of normally connected block circuits is also provided with a transformer for inductively connecting the circuit with the dispatcher's line shown at the bottom of the sheet. This connection, however, in the present instance, is under the control of a 55 dispatcher and is brought about by the operation of a railway selector S, which may be of any well known type. A pair of trucks representing respectively the front and rear ends of a train are shown in blocks C and D. Each truck represents 60 a car with an inductor, such as shown in Fig. 1. The various relays are shown in normal condition with the exception of those associated with blocks C and D, which are shown in the position which they assume on the presence of a train 65 in the respective blocks.

In Fig. 5 is shown a telephone set with transmitting and receiving amplifiers for use in the telephone systems herein described. The circuit shown is connected with the dispatcher's line referred to in Fig. 4, and also with other dispatcher's lines as will be pointed out later. It may be noted that the telephone set designated TT in Fig. 1 is identical with the set shown in Fig. 5.

Each telephone set is provided with a push button 70 which switches over the set from talking to

listening position, that is, either the receiving amplifier or the transmitting amplifier can be cut into service as required. The receiving amplifier is normally connected up to the dispatcher's line and to a loud speaker or other signal. A switch is 5 provided for switching over from the loud speaker to the telephone set. The dispatcher's selector control equipment SC is shown in skeleton form as 10 associated with the dispatcher's line of Fig. 4. This apparatus is well known in the art and, since it forms no part of this invention, a detailed description is not considered necessary.

In Fig. 6 is shown a modification of the system shown in Fig. 4. The modification consists in providing means for signalling the dispatcher from the train. The apparatus for this purpose would normally be associated only with certain blocks of the track system, as it is not considered necessary to permit the train to call the dispatcher at all times. This calling system 20 makes use of the ramp type automatic train control apparatus previously referred to and is, of course, provided only in systems using such type of automatic train control. The operation of the system disclosed in this figure, aside from the 25 above mentioned connecting arrangement is identical with that shown in Fig. 4. It may be further noted that the dispatcher's line shown at the bottom of the sheet and immediately below Fig. 6 extends to a telephone set, such as the set 30 shown in Fig. 5. It may also be noted that the train or car represented as standing in block C corresponds to the equipment shown in Fig. 1.

In Fig. 7 is shown a still further modification of the system disclosed in Fig. 4. In this case the 35 wire forming a part of the intermediate circuit is located between the rails and is carried by the ties, as shown in Fig. 2. As illustrated, only one rail is used in the present instance, although it is obvious that two rails in parallel can be used 40 equally well by placing the conductor in the center of the track. Further, the connection between the block circuits is direct instead of inductive as shown in the previous cases. The 45 block connections are so arranged that a transposition exists between adjacent blocks. The dispatcher's line and selectors which control the connections thereto are the same as those shown in Fig. 4, and the line likewise terminates in a telephone such as shown in Fig. 5. When used 50 in connection with this particular arrangement, the inductor shown in Figs. 1 and 2 is carried in a horizontal position, instead of the vertical position shown.

Fig. 8 is a further modification of the apparatus shown in Fig. 4. This arrangement contemplates the use of a three winding induction coil instead of the two winding coils used in previous cases. A further modification of the relay apparatus is shown, it being assumed that 55 the blocks are equipped with bridge relays of the normally energized type instead of the bridge and series relay shown in Fig. 4.

Before proceeding with the description of the 60 operation of the various systems, the operation 65 of the telephone set Fig. 5 will be considered. This set, which is used both for the train apparatus and for the dispatcher's line shown in the various figures, consists essentially of a receiving amplifier and a transmitting amplifier as 70 previously stated. Three stages of amplification are provided by the amplifying tubes RA1, RA2, and RA3. The various stages are transformer coupled, these transformers being of the usual iron core type particularly designed for handling 75

currents of audio frequency. The primary winding of the input transformer 5T1 is bridged across the dispatcher's line, as shown, or when the set is used connection with the train apparatus, is connected to the train inductor by means of a connecting transformer such as shown in Fig. 1. The secondary winding of the input transformer is connected up so that the voice current from the dispatcher's line will vary the grid potential 10 of the first amplifier tube RA1. The usual inter-stage transformers 5T2, and 5T3 connect up the second and third stages of amplification. An output transformer 5T4 serves to connect the last amplifying tube with the receiving apparatus. 15 It will be noted that a double pole switch DS is provided for connecting this transformer to either a loud speaker LS or to the telephone set comprising the receiver REC and transmitter TR. The switch will normally be thrown to its upper 20 position which places the loud speaker in service and consequently any signals coming in over the dispatcher's line or train inductor, will be amplified and put through the loud speaker which will serve as a signal for incoming calls. The 25 transmitter amplifier consists of two transformer coupled amplifying stages using the well known three element vacuum tube. The input transformer 5T5 has its primary winding connected in series with the transmitter TR of the telephone 30 set. A resistance R in this circuit reduces the drain on the battery. The resistance is bridged by a condenser which provides a low resistance path for the voice current. The secondary winding of the output transformer 5T7 is adapted to be 35 connected to bridge the dispatcher's line, or to the train inductor when the set is used with such apparatus, by switching relay SR. This relay is controlled by a key K associated with the telephone set and is operated only when it is desired 40 to speak over the set. Relay SR, when operated, completes the battery feed circuit for the filaments of the amplifying tubes TA1 and TA2 at its lower armature, connects the secondary winding of the output transformer 5T7 across the dispatcher's line at its upper-inner armature, and at this armature also disconnects the primary winding of the input transformer 5T1 of the receiving 45 amplifier from the line, and at the uppermost armature opens the battery feed circuit for the filaments of the amplifying tubes RA1, RA2, and RA3 of the receiving amplifier.

It is obvious from the foregoing that when receiving a message the key K is left in normal position and when transmitting a message this key is operated. The voice currents produced by the transmitter TR are amplified by the transmitting amplifier and impressed on the line or inductor in the well known manner, and such voice currents on the line are transferred to the inductor by way of the intermediate circuit or vice versa and are amplified by a receiving amplifier similar to the one shown and impressed on the receiving loud speaker or receiver of that set.

With the operation of the telephone set in mind the manner in which various calls may be made in the system disclosed will now be considered.

Referring now to Fig. 4, front and rear ends of a train are shown, respectively, in blocks C and D as previously stated. The first and last car of the train are provided with inductors I and telephone sets, such as Fig. 5, connected up as shown in Fig. 1. Assume that the trainman at the rear car TRR desires to speak with the engineer or trainman at first car or locomotive TRF of the

train. The train may be either stationary or in motion, the operation being the same in either case as long as the two inductor carrying cars are in the blocks mentioned. The calling man operates the transmitting key of his telephone set, 5 as was described under Fig. 5, and speaks into the transmitter thereby impressing an amplified current on the inductor I. This current is induced in the intermediate circuit by way of the two track rails in parallel, the circuit extending 10 from the right end of the rails of section D, through the two condensers connected thereto, normally closed middle contacts of the relay 42E, through the right-hand winding of the transformer 4TL', through the normally closed lower 15 contacts of the relay 42E, thence over the intermediate conductor 43, through the right-hand winding of the transformer 4TC, through two condensers in parallel to the left-hand end of the rails of block D. The current in the block circuit 20 is in turn induced in the block circuit adjacent to the left, this circuit extending from the left-hand winding of the transformer 4TC, through the normally closed upper contacts of the relay 4TB, through the two condensers in parallel, to the 25 left-hand end of the rails of the block C, through those rails in parallel and through the two condensers at the right end of the rails back to the left-hand winding of the transformer. The current flowing in this circuit will in turn be induced 30 into the inductor I of the front car TRF, and, after being amplified by a receiving amplifier, such as Fig. 5, operates the loud speaker LS. The calling man may transmit orders to the called man by way of the loud speaker as described, or, 35 if it is desired to hold a conversation, may so inform this party. The called man will then disconnect the loud speaker and connect up the telephone set by means of a switch, such as switch DS, and by operating the corresponding talking 40 key K of his set may speak to the calling man over the circuits just traced. The calling man in order to hear the conversation must, of course, release his talking key K, as previously explained. It will be noted that the transformer 4TL' is included in this circuit but this is without effect at 45 this time since the primary winding of the transformer is open at the contacts of the selector S'. Further the left-hand winding of the transformer 4TD is short-circuited at the normally closed lower contacts of relay 42E, thereby, keeping the 50 blocks D and E isolated. Blocks B and C are isolated by the open point in the right-hand winding of the transformer 4TB.

A block circuit may vary in length from a few 55 hundred feet to several miles depending on the conditions required for signalling purposes. In the longer circuits particularly, there is a tendency to pick up considerable inductive disturbance from near-by power lines, street car tracks or electrical machinery, in fact, unless steps are taken to overcome this difficulty, the inductive disturbances may well prevent the transmission of intelligible speech. It will be noted that the right-hand winding of the transformer 4TC is 60 connected up to the block circuit in the reverse direction with respect to the left-hand winding. This reversal has the effect of a transposition, and the inductive disturbance picked up by each block being approximately the same, the effect 65 70 will be to neutralize the disturbance and reduce the noise considerably. The voice current is not affected by this transposition and consequently reliable transmission is attained.

In the foregoing description it was assumed that 75

the inductors shown were located at different points on the same train. It is obvious, however, that the same results would be obtained if these inductors were carried by separate trains. Further the dispatcher may talk with either party in the above connection by merely operating the selector S' to connect up the left-hand winding of the transformer $4TL'$ to the dispatcher's line. In this manner, orders from the dispatcher as well as information from the trainmen may be passed back and forth.

The above described intermediate circuit would be effective with the train in either of the blocks C or D alone. With the train in block C the signal relay $41D$ would be actuated and the previously traced circuit including the conductor 43 would extend through lower and middle closed contacts of this relay. The blocks D and E would be isolated by the short-circuit around the left-hand winding of the transformer $4TD$ as before. With the train in section D alone the intermediate circuit would also be the same. In this case the relay $42C$ would be in normal position and the C block would be isolated from block B by the open point in the right-hand winding of the transformer $4TB$ as before. With the train either block alone as above, the blocks C and D are still inductively connected with a transposition which neutralizes the inductive disturbance picked up by the intermediate circuit.

It is obvious from the drawings that alternate sections of the intermediate circuit or individual block circuits correspond, that is, section A, B, and E are similar in every respect and sections C, D, and F are similar. The circuits for adjacent blocks in dissimilar sections, such as C and D are in permanent transposed inductive relationship, as described. Assuming now that the train is moving from block C into block B, relay $41B$ will be short-circuited by the trucks of the locomotive or the first car of the train, as the block is entered, and that relay will become deenergized. Relay $41B$ at its upper-back contacts will open a point in the previously described intermediate circuit of block C, and will include the right-hand winding of the transformer $4TB$ in this circuit. The short-circuit will be removed from the left-hand winding of the transformer $4TB$ at the lower-back contacts of the relay, and the short-circuit will be removed from the right-hand winding of the transformer $4TL$ by the middle-back contacts. The intermediate circuit of the block B will then be exactly the same as that previously described for block D and the circuit of the block A will be the same as that of the block C as described for the train in block D alone. It, therefore, follows that the intermediate circuits of these four blocks A to D, inclusive, are now inductively connected by the transformers $4TA$, $4TB$, and $4TC$. The windings of the transformer $4TC$ are connected in reverse directions to the adjacent block circuits, as are those of transformers $4TA$ and $4TB$. Two additional transpositions are, therefore, inserted in the circuit which extends over four blocks. Conversation may be held between the front and rear of the train as in the previous instance, or the dispatcher may call by operating the selector S' , as in the previous instance. Similar conditions will prevail with the train in block B for example and another train in block C or D. As the rear end of the train leaves block C and enters into block B, the circuit of block C reverts to its normal condition, which is the same as that shown for the intermediate circuit of block E. The re-

lay $42C$ will be deenergized and will short-circuit the left-hand winding of the transformer $4TB$, at the same time removing the short-circuit from the right-hand winding of the transformer $4TL$. The inductive connection between the intermediate circuits B and C will, therefore, be disabled and the talking circuit will include only the circuits of the blocks A and B, respectively. The dispatcher will connect to this circuit by operating the selector S to connect up the left-hand winding of the transformer $4TL$. Thus regardless of the length of the train or the direction in which it is moving, an even number of transposed sections will always comprise the intermediate circuit, which being thus balanced will effectively neutralize any inductive disturbance which may be picked up either by the intermediate conductor carried on the pole line, or by the rails.

Referring now to Fig. 6 it will be seen that the signal relay apparatus shown here is identical with that shown in Fig. 4, above described. A relay such as the relay $63B$ is bridged across the rails of each block together with a source of current or battery. Alternate blocks such as C and E are provided with a relay such as $64C$ in series with the bridged battery. These relays have the same function of connecting up the adjacent intermediate circuits as the corresponding relays of the system disclosed in Fig. 4. In addition the railroad has been shown equipped for automatic train control by the intermittent contact method. This control apparatus is similar to that shown in the Bulletin No. 5 of the American Railway Association above referred to. The roadside equipment consists essentially of a ramp to which battery of either positive or negative polarity may be connected, while at the same time battery of an opposite polarity is connected to one of the track rails. The train carries a shoe for engaging the ramp and relay equipment which is controlled by the current encountered on the ramp and track rail. The train control apparatus is modified to permit signalling the dispatcher from the train by providing a generator adapted to be bridged across the connection to the car trucks and the shoe by means of the key $6K$. An impedance $6P$ is inserted in the automatic control circuit to prevent false operation from the alternating signalling current. The wayside equipment is modified by connecting a relay $61D$ in series with a condenser across the track rails and the ramp. A impedance $6P1$ is also connected in the relay circuit of this apparatus to prevent false operation from the alternating signalling current. It will be recalled that the dispatcher on operating a selector, such as S or S' of Fig. 4, connected up the speaking transformer $4TL$ or $4TL'$ to the dispatcher's line. In the present case the selectors S and S' are arranged to complete a circuit for a connecting relay which performs the function of connecting the intermediate circuit to the dispatcher's line. This connecting relay is also operable under control of the relay $61B$ or $61D$ which is adapted to be operated by the generator connected to the automatic train control apparatus. The purpose of this arrangement is to make it possible for the trainmen to call the dispatcher in certain blocks. That is, it is unnecessary for the trainmen to wait for the dispatcher to complete a connection when such is desired.

Adjacent intermediate circuits are connected in pairs through a reversing transformer, as described under Fig. 4, and additional pairs are connected or disconnected as the train moves

through the various blocks, exactly the same as previously described. To initiate a call from the train to the dispatcher's office the trainman will actuate key 6K as the train enters the block D. Current will flow from the output side of the generator through the shoe SH and the ramp RA engaged by the shoe, through the relay 61D and its associated condenser, through the track rails and wheel and axle of the car truck, to the key 6K and back to the generator. As previously inferred, this alternating current will not affect the automatic train control apparatus, but will operate the relay 61D. Further the entry of the train into the block D will cause the deenergization of the relay 63D in the usual way, which relay will function to connect up the adjacent block circuits and at the same time will prepare a locking circuit for the relay 62D. Relay 61D on operating will close an energizing circuit for relay 62D, and that relay will operate and lock by way of its upper-front contacts and the lower-back contacts to the relay 63D. Relay 62D at its middle-front contacts will connect the left-hand winding of the transformer 6TL1 across the conductors of the dispatcher's line and at its lower-back contacts will remove the short-circuit from the right-hand winding of that transformer. By operating the talking key of the telephone set the trainmen can now call over the intermediate circuit and the dispatcher's line. The operating circuit of relay 62D may also be completed by the dispatcher on operating the selector S1. A talking circuit, of course, is completed only at times when there is a train in the block and the relay 63D is deenergized. This is of no consequence since there is no occasion for a talking circuit unless there is a train in the block.

Talking connections between the head and rear end of the train, or between separate trains in adjacent sections, will be completed exactly as described for Fig. 4. In this case no signalling current will be applied to the relay 61D, and consequently the connecting relay 62D will not be operated. It may be noted that under these conditions the right-hand winding of the transformer 6TL1 is short-circuited. This arrangement improves transmission by removing an unnecessary impedance from the talking circuit. The various block circuits are connected in transposed pairs and paired circuits are likewise connected in transposed relationship when required.

In Fig. 7 is shown a stretch of track divided into blocks A to F, inclusive, each block being provided with two normally energized bridged relays for signalling purposes. These relays will become deenergized as the train passes through a block and complete circuits for talking purposes. Assume that the train is in block C, as illustrated and relays 71C and 72C are deenergized. When the telephone set of the train, corresponding to the set shown in Fig. 5, is connected in talking relation and current is impressed on the inductor II, corresponding current is induced in an intermediate circuit, which may be traced from the lower rail 2 of block C, through the condenser at the right end of the rail, through the upper-back contacts of relay 71C and upper-front contacts of relay 72D, through the upper winding of transformer TRL2, thence through conductor 73 which is carried on the ties parallel to the rails and located adjacent to the upper rail 2', thence through the upper-back contacts of relay 72C and upper-front contacts of relay 71B, through the condenser, to the left-hand end of the rail 2. With the train completely in this block a talking

circuit exists between the front end and the rear end of the train over this inductive intermediate circuit. The dispatcher may also complete a talking connection with the train in this block by operating the selector S2 which connects up the lower winding of the transformer TRL2 with the dispatcher's line. As the train moves into block D, there will be a period when both blocks are occupied, and relays 71D and 72D in addition to relays 71C and 72C will be deenergized. The previously traced intermediate circuit instead of extending through the upper-make contacts of relay 72D will be extended through the upper-back contacts by way of conductor 74 which corresponds to conductor 73 of block C, thence through the upper winding of transformer TRL3, upper-front contacts of relay 72E, upper-back contacts of relay 71D, through the condenser to the right-hand end of the rail 2 of block D, thence through the condenser at the left-hand end of this rail and the lower-back contacts of relays 71C and 72D to conductor 73. It will be seen that a transposition exists between these two circuits, that is, current flowing through conductor 73, block C, will flow through the rail of block D and then through the conductor 74 of the block D and back to the rail of block C. Talking circuits between the front and rear of the train or between separate trains of these two blocks may be completed in the usual way. The dispatchers may also connect to this circuit by operating selector S3 which bridges the lower winding of the transformer TRL3 across the dispatcher's line. As the end of the train leaves block C, relays 71C and 72C will again become energized and disconnect the intermediate circuit of the block from that of block D which will now correspond to the circuit first described for block C. Thus as the train moves along the intermediate circuit will be prepared and when necessary will be connected only in the blocks occupied by the train.

The above described arrangement is particularly adapted for use in systems using long block sections in which the inductive interference is relatively small. The use of the conductor between the rails is similar to that of a conductor on a pole line, although it is obviously less expensive to use the conductor as shown. In the modification shown in Fig. 7 the train inductor instead of being mounted vertically, as shown in Fig. 1 will be mounted horizontally so that opposite sides will affect the two sides of the circuit comprising the conductor 73 and the rail 2. Alternatively the inductor may be mounted vertically directly over the rail or over the conductor, so that the influence will be confined to one side of the circuit. It is obvious that two rails in parallel may be used in this type of connection, in which case the conductor will be carried down the center of the track and the inductor will be carried vertically over this conductor.

The system disclosed in Fig. 8 is in general similar to that of Fig. 4 of which it is a modification. The signal relay apparatus shown is similar to that of Fig. 7. In this case, however, each block circuit is normally isolated from adjacent circuits, but in the case of a block being occupied by a train, two circuits are inductively connected with a transposition. This arrangement may be used to advantage when the inductive disturbances picked up by the intermediate circuit are relatively uniform throughout its length. In addition, connection with the dispatcher's line is made by means of a third winding on the block con-

necting transformers by the presence of a train in the associated block. In other words, the train and the dispatcher are telephonically connected at all times.

5 By way of example, a train is assumed to be occupying block C. The front car or locomotive of the train is provided with a telephone set as Fig. 5 and an inductor such as shown in Fig. 1. When the talking key K of the telephone set is 10 operated and the transmitter spoken into, the transmitting amplifier impresses current on the inductor I in the usual way and this current in turn is induced in the two track rails of the block C in parallel. A closed loop circuit may be traced 15 from the right-hand ends of the rails of this block, through the parallel condensers connected thereto, through the left-hand winding of transformer 8T3, conductor 83, right-hand winding of transformer 8T2, lower-back contacts of relay 20 82C, through the two condensers to the left-hand end of the rails of block C. A similar circuit for block B is inductively connected to the above circuit in transposed relationship, this circuit extending from the left-hand winding of transformer 25 8T2, conductor 84, lower front contact of relay 82B, through the two condensers to the left-hand end of the rails of block B, through these rails in parallel and the two condensers connected to the right end thereof, to the left-hand winding of 30 the transformer. Since relay 81 is deenergized and relay 82D is energized, the middle winding of transformer 8T3 will be bridged across the dispatcher's line. This arrangement provides a continuous talking connection between the train and 35 the dispatcher's office. Since trains in other blocks are similarly connected to the dispatcher's line, messages may be transmitted between trains by way of the dispatcher's line when the trains occupy non-adjacent blocks.

40 Having described the invention, what is considered new and is desired to have protected by Letters Patent is set forth in the following claims:

What is claimed is:

1. In a telephone system for communicating 45 between a moving train and a wayside point, the combination with a transmitting and receiving set on the train, of a transmitting and receiving set at the wayside point, a line for said second set, a plurality of intermediate circuits for individually inductively connecting the two sets via said line, and means for inductively connecting two of 50 said intermediate circuits over a path independent of said line.

2. In a telephone system for communicating 55 between a moving train and a wayside point, the combination with a transmitting and receiving set on the train, of a transmitting and receiving set at the wayside point, a line for said second set, a plurality of intermediate circuits each associated with a particular section of track, said circuits being individually adapted to connect with said line for inductively connecting said two sets when the train occupies the associated track section, and means for inductively connecting adjacent circuits independent of said line when a 60 train occupies the adjacent track sections associated with said circuits.

3. In a telephone system for communicating 70 between a moving train and a wayside point, a transmitting and receiving set on the train, a transmitting and receiving set at the wayside point, a plurality of intermediate circuits each associated with a particular section of track and adapted to be inductively connected to said first 75 set when the train occupies the section, means

for inductively connecting the intermediate circuit of the occupied section with said second set, and means controlled by the train for inductively connecting adjacent circuits when the train moves into the adjacent section and simultaneously occupies both sections and for disabling the last-mentioned means of one of the circuits. 5

4. In a telephone system for communicating between a moving train and a wayside point, a telephone set on the train, a telephone set at the wayside point, a plurality of intermediate circuits each associated with a particular section of track and inductively connected with said first set when a train occupies the section, means for inductively connecting the circuit associated with 10 the occupied section with said second set, means controlled by the train for inductively connecting the circuits associated with adjacent sections occupied by the train, and means for disabling said connection with the second set responsive to the 15 connection of said adjacent sections.

5. In a telephone system for communicating between a train and a wayside point, a telephone set on the train, a telephone set at the wayside point, a plurality of intermediate circuits each 20 associated with a particular section of track and adapted to inductively connect said two telephone sets when the train moves through the associated section, and means for inductively connecting adjacent circuits in transposed relationship 25 when a train moves from one section to another and simultaneously occupies two sections. 30

6. The combination with a railroad track divided into a plurality of electrically insulated 35 sections, of a separate closed electrical circuit including the track rails for each section, said circuits being adapted for inductively connecting with a telephone set carried by a train occupying the associated section, and means for inductively 40 connecting adjacent circuits when adjacent sections are simultaneously occupied by a train or trains. 45

7. The combination with a railroad track divided into a plurality of electrically insulated sections, of a plurality of closed electrical circuits 50 including the track rails of the respective sections, said circuits being adapted for inductively connecting with a telephone set carried by a train occupying the associated section, and train controlled means for inductively connecting adjacent sections in transposed relationship. 55

8. The combination of a railroad track divided into a plurality of electrically insulated sections, of a train moving along said track, a telephone 55 set on said train, a separate closed circuit including track rails for each section inductively connected with said telephone set, and train controlled means for inductively connecting adjacent circuits responsive to the train moving from one 60 section to another and simultaneously occupying both sections and for disconnecting the last circuit when the associated section is vacated.

9. In an inductive telephone system for communicating between different points on a moving 65 train, an intermediate circuit including track rails for inductively connecting the telephones at said different points, and means for automatically inserting transpositions in said circuit as the train moves along the track. 70

10. In an inductive telephone system for communicating between a moving train and a wayside point, an intermediate circuit including track rails inductively connecting the telephone set on the train with the telephone set at the way- 75

side point, and means for automatically inserting transpositions in said circuit as the train moves along the track.

11. The combination with a railroad track divided into a plurality of electrically insulated sections, of a separate closed electrical circuit for each section including the track rails of the section, an intermediate circuit normally comprising a pair of adjacent sectional circuits inductively connected in transposed relationship, and automatic means for inductively connecting a plurality of said intermediate circuits.

12. The combination with a railroad track divided into a plurality of electrically insulated sections, of a separate closed electrical circuit for each section including the track rails of the section, said circuits being normally connected in pairs with a transposition between the circuits, and automatic means for connecting adjacent paired circuits in transposed relationship.

13. The combination with a track comprising a plurality of electrically insulated rail sections, a closed electrical circuit for each section including the rails of the section, said sections being of two different types arranged in alternate positions, an intermediate circuit normally comprising one circuit of each type inductively connected with a transposition, and automatic means for expanding said intermediate circuit to include a plurality of circuits of each type inductively connected with transpositions between circuits.

14. In a railroad telephone system, a track comprising a plurality of electrically insulated rail sections, a closed electrical circuit for each section including the track rails of the section, and a traveling intermediate circuit adapted to inductively connect with a telephone set carried by a train, said intermediate circuit comprising an even number of transposedly connected sectional circuits.

15. In a telephone system for communicating between a moving train and a wayside point, a telephone set on the train, a telephone set at the wayside point, an intermediate circuit including track rails, inductively connected with said first set, train controlled means for inserting transpositions in said circuit, and means controlled from the train for inductively connecting said circuit with said second set.

16. In a telephone system for communicating between a moving train and a wayside point, a telephone set on the train, a telephone set at the wayside point, an intermediate circuit including track rails inductively connected with said first set, means controlled by the train for inserting transpositions in said circuit, and means controlled separately from either the train or the wayside point for inductively connecting said circuit with said second set.

17. In a telephone system for communicating between moving trains and between such trains and a wayside point, telephone sets on the trains, a telephone set at the wayside point, a traveling intermediate circuit including track rails inductively connecting said first sets, said circuit comprising an even number of transposed sections, and train controlled means for increasing or decreasing the number of sections in said circuit.

18. In a telephone system for communicating between the head and rear ends of a train or between either end of the train and a wayside station, telephone sets at each end of the train and at the station, a wayside telephone line connected with said station set, intermediate circuits each associated with a particular section of a

track, means for inductively connecting the train sets with the intermediate circuit associated with the particular section of the track occupied by the respective ends of the train, means effective when the train occupies a plurality of sections of track for inductively connecting the associated circuits to complete a talking connection between the head and rear ends of the train, and means effective when the train occupies a plurality of sections of track for connecting only one of the associated circuits to said line to complete a talking connection between either end of the train and said wayside station.

19. In a telephone system for communicating between a moving train and a wayside station, a temporary connection between a transmitting and a receiving set on the train and a transmitting and receiving set at the wayside station comprising a plurality of closed loop circuits inductively connected together in series relationship, and a telephone line inductively connected with one of said circuits.

20. In a telephone system for communicating between a moving train and a wayside station, a temporary circuit connecting the train and wayside station comprising a plurality of closed loop circuits associated with a particular section of track, said circuits being inductively connected in series relationship, a telephone line inductively connected with one of said circuits, transmitting and receiving sets on the train and at the wayside station adapted to be inductively connected to one of said circuits and to said line respectively, and means associated with each set for determining whether the connection shall be for transmitting or for receiving purposes.

21. In an inductive telephone system for communicating between two points on a moving train, an intermediate circuit inductively connecting telephone sets at said points, and means for automatically inserting transpositions in said circuit as the train moves along the track.

22. In an inductive telephone system for communicating between two points on a moving train, a plurality of stationary section circuits, and means for progressively connecting adjacent section circuits in transposed relationship as the train moves along the track to constitute a traveling intermediate circuit for inductively connecting telephone sets at said two points.

23. The combination with a railroad track divided into a plurality of sections, a separate closed electrical circuit for each section adapted to inductively connect with a telephone carried by a train occupying the associated track section, and means for connecting adjacent circuits in transposed relationship when adjacent sections are occupied by a train or trains.

24. In an inductive telephone system for communicating between two points on a moving train and between either or both of said points and a wayside station, telephone sets at said two points and at said wayside station, a line for said station telephone, an intermediate circuit inductively connected with said first two telephones and with said line, and train controlled means for inserting transpositions in said circuit as the train moves along the track.

25. The combination with a railroad track divided into sections, of a separate communicating circuit for each section including the track rails of the section, a normally energized relay bridged across the track rails of one section adapted to be deenergized responsive to the occupation of the section by a train, a normally deenergized relay

bridged across the track rails of an adjacent section adapted to be energized responsive to the occupation of the section by a train, circuit connections normally effective to isolate said communicating circuits, and contacts controlled by said relays for opening said circuit connections.

26. In combination, two adjacent sections of railroad track, a source of current connected across the rails at one end of one section, a relay connected across the rails at the other end of said one section, a relay and a source of current connected in series across the rails at one end of the other section, a telephone circuit for each section including the track rails of the section, means for preventing current flow from one telephone circuit to the other, and means controlled by said relays jointly for disabling said preventing means.

27. In a train telephone system, a track comprising a plurality of sections, a circuit for each section including the track rails of the section, means on a train for inducing voice currents in the circuit of a section occupied by the train,

means for confining said current to the occupied section, relays for adjacent track sections controlled by the occupancy of their respective sections, and means controlled by said relays jointly for permitting the currents induced in the circuit of one section to flow in the circuit of the adjacent section when both sections are occupied simultaneously by a train.

28. The combination, in a railway signal system, comprising a plurality of blocks, of a loop circuit in each block, means for supplying oscillations from a vehicle in any block to the loop circuit of the respective block, means for relaying oscillations from each loop circuit to the loop circuit of an adjacent block, means on each vehicle responsive to oscillations received from another vehicle through said loop circuits, and means responsive to the presence of a vehicle in any block to prevent oscillations transmitted by a vehicle in another block from being transmitted past the block which is occupied by said first mentioned vehicle.

WILLIAM C. PHEBUS.
